CLAIM

The ornamental design for a neck finish of a bottle, substantially as shown and described.

DESCRIPTION

FIG. 1 is a front perspective view showing the neck finish of a bottle in accordance with the present invention;

FIG. 2 is a front side view thereof;

FIG. 3 is a front side cutaway view thereof;

FIG. 4 is a rear side cutaway view thereof;

FIG. 5 is a top view thereof;

FIG. 6 is a bottom view thereof; and,

FIG. 7 is a perspective view thereof with the rest of a bottle and capped in accordance with the present invention.

The outer surface of the neck finish is of uniform cross-section, as on the view shown in FIG. 2. The broken lines in the figures showing the rest of the bottle finish, and the cap in FIG. 7, form no part of the claimed design. In FIGS. 3 and 4, the broken lines also represent a sectional designation of the cutaway portion that forms no part of the claim.
